UNITED STATES PATENT OFFICE

2,300,641

REFRIGERATOR CAR STRUCTURE

Charles D. Bonsall, Chicago, Ill., assignor to
Standard Railway Devices Company, a corpora-
tion of Delaware

Original application July 24, 1939, Serial No.
286,138, now Patent No. 2,256,376, dated Sept.
16, 1941. Divided and this application June 11,
1941, Serial No. 397,522

9 Claims. (Cl. 62—17)

This invention relates to refrigerator cars used to transport perishable commodities at a predetermined temperature. The essential features of a refrigerator car are an insulated body to prevent or retard ingress of heat during warm weather and egress of heat during cold weather and a cooling means and a heating means to be used during warm and cold weather respectively.

This invention applies particularly to cars in which the cooling means, preferably containers for water ice, eutectic ice, brine or dry ice, are disposed immediately below the roof of the car. The lading is supported in spaced relation to the floor by a foraminous rack. Flues, preferably associated with the side walls of the car, communicate between the cooling means and the space under the floor rack to provide a path for the circulation of air. The path is from the cooling means downwardly through the aforementioned flues, through the space under the floor rack, upwardly through the lading compartment thereby cooling the lading, and finally to the cooling means from where the cycle is repeated.

The refrigerant used in a car of this type usually weighs as much as several tons so that it is essential that the structure supporting the refrigerant have considerable strength. In addition to the dead weight of this mass there are dynamic forces of great magnitude, both vertically and horizontally, which are caused by acceleration and deceleration of the car and by sudden starting and stopping as well as swaying of the car. The hazards in a car of this type due to the above conditions are particularly great because of the danger of the containers dropping from their overhead position onto the lading.

It is also essential, in addition to having the tanks securely supported, to have them supported so that they may be readily removed and replaced. Damage to the tanks may be caused by the shifting of the great mass of refrigerant or by the impact which occurs when large pieces of refrigerant are dropped through the hatches into the containers. Corrosion is another factor which necessitates the containers being readily removable and replaceable. Salt, which is often used with the refrigerant, has a very corrosive effect on many materials and often results in rapid deterioration.

It is an object of the invention to support the containers on a solid base; that is, one in which the weight of the refrigerant and the refrigerant container is supported by substantially horizontal surfaces resting upon other such surfaces. This is considered an improvement over a construc-

tion in which the containers are supported by the shear strength of bolts or rivets. Another object is to provide means for bracing the refrigerant containers against the lateral thrusts which occur due to the inertia of a shifting refrigerant in the container. A further object of the invention, in addition to bracing the containers against horizontal and vertical thrusts, is to provide means by which the containers may be lowered vertically out of position after a relatively small lateral movement thereof.

Drip pans, which are usually disposed below the containers, commonly have, for a purpose to be hereinafter described, partitions upstanding therefrom at certain edges thereof. It is essential for the protection of the lading from liquid that the joint between the drip pans and the partitions be watertight. An object of the invention is to provide carlines for supporting the containers, said carlines being disposed near the roof of the car so that substantially all of the aforementioned partitions are below the carline, thereby eliminating the necessity of a watertight joint between the partitions and carlines.

In the drawing:

Fig. 1 is a transverse section through the upper part of a refrigerator car embodying my invention.

Fig. 2 is a plan section on line 2—2 of Fig. 1.

The general parts of the refrigerator car shown are insulated roof 2, side walls 3, hatches 5, refrigerant containers 6 and side wall flues 8. The refrigerant containers 6 are positioned directly below the roof 2 and adjacent the side walls 3. A drip pan 9 is provided below each container 6 and a partition 11 is secured in an upstanding position at the edge of each drip pan 9. The drip pans 9 and partitions 11 cooperate with the roof 2 and side walls 3 to form enclosing structures 12 around the containers 6, air inlet openings 14 being provided by spacing the partitions 11 from the roof 2. Air discharge openings 15 which lead to the flues 8 are formed by spacing the drip pans 9 from the walls 3.

The side walls 3 comprise outer sheathing 20, outer sideplates 21, posts 22, inner sheets 23 and inner side plates 24. Channel-shaped carlines 26 having depending ends 28 extend between the inner side plates 24 and are secured thereto. Brackets 30 for supporting the sides 29 of refrigerant containers 6 adjacent the side walls 3 of the car are secured to the inner side plates 24 and the depending ends 28 of the carlines 26. Each bracket 30 comprises a transversely extending plate 31, a vertically disposed flange 32 which is

secured to an inner side plate 24 (and carline 26) by some means, such as rivets 34, and a substantially horizontal shelf 35. At the center of the car, preferably extending on both sides of the center line thereof, gussets 38 are secured to the carlines 26 by the rivets 39 through flanges of the gussets or by other means. Each gusset 38 has a depending portion 41 which is provided with a substantially horizontal shelf 42 for supporting a container 6. The upstanding partitions 11 may also be supported by the depending portions 41.

The refrigerant containers 6 are preferably formed of sheet metal with the bottoms 45 thereof reinforced by a plurality of spaced apart, transversely extending channel members 46, the channel members 46 being disposed with their webs 47 vertical and having their ends formed as horizontal feet 48. Reinforcing members 50 may be secured to the sides 51 of the container 6, which reinforcing members 50 comprise angles each having one leg 52 secured to a container 6 and the other leg 54 disposed in flatwise relation to the web 47 of a channel reinforcing member 46. The angle reinforcing members 50 have substantially horizontal feet 56 which lie between the shelves 42 and the flanges 57 of the channel reinforcing members, thereby providing very rigid footings upon which the containers rest. Bolts 59 are preferably provided to secure together the shelves 35, 42, flanges 57 and feet 56. Other bolts 60, extending in a horizontal direction, resist lateral thrusts resulting from the mass of refrigerant in refrigerant containers.

In order to remove a container 6, it is necessary only to remove the bolts 59, 60, move the container 6 laterally toward an end of the car a distance slightly more than the width of the shelves 35, 42 and then lower said container in a vertical direction to the floor of the car.

It is quite important to the refrigerating efficiency of a car of this type that the upper edges of the partitions 11 be at a considerably higher level than the openings 15 to the flues 8. It is equally important that the joints between the partitions 11 and the drip pans 9 be watertight to prevent leakage from the containers 6 to the lading. For this purpose, I secure the gussets 38 to the carlines 26 in depending positions and attach the containers to the depending portions 41 of the gussets. The partitions 11 are disposed between and supported by the depending portions 41.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

This is a division of my application filed July 24, 1939, Serial No. 286,138, which has matured into Patent No. 2,256,376.

I claim:

1. In a refrigerator car, spaced apart walls, a roof extending therebetween, a refrigerant container below said roof and adjacent one of said walls, spaced apart brackets secured to said last mentioned wall, said brackets having substantially horizontal shelves, gussets depending from said roof remote from said wall and having substantially horizontal shelves, members projecting beyond the sides of said container, said members having substantially horizontal feet which rest upon said shelves to support the container and substantially vertical parts engaging said

brackets and said gussets to resist horizontal inertia thrusts of the container, said feet and shelves being arranged to be disengaged upon lateral movement of said container after which said container may be moved vertically out of position.

2. In a refrigerator car, spaced apart walls, a roof extending therebetween, a refrigerant container below said roof and adjacent one of said walls, spaced apart brackets secured to said last mentioned wall, said brackets having substantially horizontal shelves, gussets depending from said roof remote from said wall and having substantially horizontal shelves, members projecting beyond the sides of said container, said members having substantially horizontal feet which rest upon said shelves to support the container, said feet and shelves being arranged to be disengaged upon lateral movement of said container after which said container may be moved vertically out of position.

3. In a refrigerator car, spaced apart walls, a roof extending therebetween, a refrigerant container below said roof and adjacent one of said walls, spaced apart brackets secured to said last mentioned wall, said brackets having substantially horizontal shelves, gussets depending from said roof remote from said wall and having substantially horizontal shelves, the bottom of said container being reinforced by laterally extending members having their ends projecting beyond the sides of said container, said ends having substantially horizontal feet which rest upon said shelves to support the container, said feet and shelves being arranged to be disengaged upon lateral movement of said container after which said container may be moved vertically out of position.

4. In a refrigerator car having spaced apart walls, including inner side plates, a roof extending between said walls, spaced apart carlines extending between and supported by said walls adjacent the upper part of the car, a pair of spaced apart refrigerant containers below said roof, one adjacent each of said walls, a bracket rigidly secured to each of said side plates and including a plate extending transversely to the wall, a gusset depending from and rigidly secured to one of said carlines and including portions extending transversely to said walls and members rigidly secured to said containers and having legs arranged flatwise with and removably secured to said plates and portions respectively.

5. In a refrigerator car having spaced apart walls, a roof extending between said walls, a pair of spaced apart refrigerant containers below said roof, one adjacent each of said walls, a bracket rigidly secured to each of said walls and including a plate extending transversely to the wall, an inverted U shape gusset depending from and rigidly secured to said roof and including spaced apart portions extending transversely to said walls, a pair of spaced apart partitions disposed between and respectively supported by said portions, drip pans below said containers cooperating with said partitions to at least partially enclose said containers and members rigidly secured to said containers and having legs arranged flatwise with and removably secured to said plates and portions respectively.

6. In a refrigerator car having spaced apart walls, a roof extending between said walls, a pair of spaced apart refrigerant containers below said roof and respectively adjacent said walls, a bracket rigidly carried by said car adjacent each of

said walls, gusset means rigidly carried by the car and including depending portions disposed in spaced apart relation between said containers, members rigidly secured to said containers and removably secured to said brackets and portions respectively to support the containers, drip pans spaced below said containers to provide air cooling spaces therebetween and partitions disposed between said portions in spaced apart relation to form a duct for directing air from the interior of the car to said air cooling spaces.

7. In a refrigerator car having spaced apart walls, a roof extending between said walls, a pair of spaced apart refrigerant containers below said roof and respectively adjacent said walls, a bracket rigidly carried by said car adjacent each of said walls and including a plate extending transversely to the wall, gusset means rigidly carried by the car and including depending portions extending transversely to said walls and disposed in spaced apart relation between said containers, members rigidly secured to said containers and having legs arranged flatwise with and removably secured to said plates and portions respectively to support said containers, drip pans spaced below said containers to provide air cooling spaces therebetween and partitions disposed between said portions in spaced apart relation to form a duct for directing air from the interior of the car to said air cooling spaces.

8. In a refrigerator car having spaced apart walls, a roof extending between said walls, a pair of spaced apart refrigerant containers below said roof, one adjacent each of said walls,

5 a bracket rigidly carried by said car adjacent each of said walls and including a plate extending transversely to the wall, gusset means rigidly carried by the car and disposed between the 10 containers, said means including a pair of depending spaced apart portions extending transversely to said walls, a pair of spaced apart partitions disposed between and respectively supported by said portions, drip pans below said containers cooperating with said partitions to at least partially enclose said containers and members rigidly secured to said containers and having legs arranged flatwise with and removably secured to said plates and portions respectively to support said containers.

9. In a refrigerator car having spaced apart walls, a roof extending between said walls, a pair of spaced apart refrigerant containers below said roof, one adjacent each of said walls, a bracket rigidly carried by said car adjacent each of said walls and including a plate extending transversely to the wall, gusset means rigidly secured to said roof and including a pair of depending spaced apart portions extending transversely to said walls, a pair of spaced apart partitions disposed between and respectively supported by said portions, drip pans below said containers cooperating with said partitions to at least partially enclose said containers and members rigidly secured to said containers and having legs arranged flatwise with and removably secured to said plates and portions respectively to support said containers.

CHARLES D. BONSALL.
